(57) **CLAIM**

We claim the ornamental design for a floating gems purse pendant, as shown.

DESCRIPTION

FIG. 1 is a front view of the floating gems purse pendant.

FIG. 2 is a top view of the floating gems purse pendant.

FIG. 3 is a bottom view of the floating gems purse pendant.

FIG. 4 is a side perspective view of the floating gems purse pendant; and,

FIG. 5 is a back view of the floating gems purse pendant. The hexagons are indicative of gems floating and are not in a fixed position.
